UNITED STATES PATENT OFFICE.

FREDERICK STANDISH, OF SHELTON, CONNECTICUT.

REVERSIBLE CUFF.

1,307,934.

Specification of Letters Patent. Patented June 24, 1919.

Application filed January 17, 1919. Serial No. 271,743.

To all whom it may concern:

Be it known that I, FREDERICK STANDISH, a subject of the King of Great Britain, residing at Shelton, in the county of Fairfield 5 and State of Connecticut, have invented certain new and useful Improvements in Reversible Cuffs, of which the following is a specification.

The object of the present invention is to 10 provide means whereby a cuff may be worn for a longer period than is now possible with the ordinary cuff and to so construct the shirt sleeve to which the cuff is attached that the unexposed portion of the cuff will 15 be kept clean. These stated objects and such other objects as will incidentally appear in the course of the following description are attained in the device illustrated in the accompanying drawings and the invention 20 resides in certain novel features which will be particularly pointed out in the appended claim.

In the drawings—

Figure 1 is a perspective view of the lower 25 end of a shirt sleeve with a cuff attached and embodying my invention;

Fig. 2 is a similar view showing a different arrangement of the cuff and shirt sleeve;

Fig. 3 is an enlarged view, partly in section and partly broken away;

Fig. 4 is a detail view showing a different embodiment of the invention;

Fig. 5 is an enlarged section of the arrangement shown in Fig. 4.

In carrying out my invention, I attach to 35 the shirt sleeve 1, which may be constructed in the usual manner except as hereinafter particularly set forth, an inner apron 2 which may be provided with a wrist band 3 at its lower end and is attached by stitching 4 at its upper end to the inside of the shirt sleeve. This apron is provided with an opening 5 corresponding to the usual opening 6 of the shirt sleeve and the wrist 45 band may be provided with button holes 7 as will be readily understood. In the form of the invention shown in Figs. 1, 2, and 3, the cuff 8 is attached by stitching 9 to the edge of the shirt sleeve and may be constructed in the same manner as the ordinary attached cuffs now in common use, except that it is made twice the width of the ordinary cuff and when it is first worn is disposed, as shown in Fig. 3, with the upper 50 half 10 of the cuff housed within the pocket formed by the shirt sleeve and the apron 2.

When thus arranged, the cuff will appear as shown in Fig. 2 and the portion exposed below the coat sleeve will have the same finish and style as the ordinary cuff. When the exposed lower portion or edge of the cuff has become soiled so as to be no longer slightly, the buttons, indicated at 11, are removed and the cuff is then reversed so that the portion 8 previously exposed will lie 60 against the outer portion of the lower end of the shirt sleeve, as indicated in Fig. 1, the portion 10 previously housed within the pocket being exposed so that to all appearances the wearer will have a new pair of 65 cuffs. The upper end of the apron 2 should be so disposed that this apron may be readily flexed to permit reversal of the cuff but will extend over the entire upper half of the cuff and prevent the same being soiled by 70 contact with the skin of the wearer or from other causes, while, as is obvious, the shirt sleeve will protect the upper half of the cuff from any soiling by reason of contact 75 with the coat sleeve or other external causes. 80

In the embodiment of the invention shown in Figs. 4 and 5, the shirt sleeve is provided with an apron 11' on its inner side, the same in all respects as the apron 2. In this form, however, the shirt sleeve is provided with a wrist band 12 and may have a button hole 13 at its center to receive a stud or button 14 at the center of the cuff. The cuff will be of any well-known or preferred shape except that it will be twice the width of the 90 cuff ordinarily employed and will be provided with a central opening to receive the stud or button 14, as shown at 15. This detachable cuff is arranged in the same manner as the attached cuffs shown in Figs. 1, 95 2, and 3 so that the unexposed half of the cuff will be housed within the pocket formed by the end of the shirt sleeve and the apron 11'. When the lower portion of the cuff has become soiled, the button 14 is removed 100 so as to permit the cuff to be withdrawn. The cuff buttons are then shifted to the opposite edge of the cuff and the cuff reversed so that the soiled edge of the same will be housed within the pocket, the button 14 replaced and the cuff will then be 105 ready for use.

It will be readily noted from the foregoing description, taken in connection with the accompanying drawings, that I have 110 provided a very simple and inexpensive means whereby a reversible cuff may be

worn and the portion of the cuff which is not exposed below the coat sleeve will be kept perfectly clean. The cuffs may, consequently, be worn twice as long as is now ordinarily the case so that the cost of laundering will be reduced and the life of the cuffs and the shirt in connection with which they are worn will be prolonged. The use of my invention does not detract from the fit or style of the garment and it may be worn by any one without discomfort. By making the parts of proper proportions, the button 14 may be exposed below the coat sleeve and persons so disposed will thus be permitted to display jewelry. The in-

vention may be applied to ladies' waists and dresses by fastening a sleeve embodying the invention inside the sleeve of the dress or waist.

Having thus described the invention, what is claimed as new is:

The combination with a shirt sleeve, of an apron secured at its upper end to the inside of the shirt sleeve and having its lower end free of the shirt sleeve, a cuff having one-half housed between the apron and the shirt sleeve, and means for attaching the cuff to the shirt sleeve.

In testimony whereof I affix my signature.
FREDERICK STANDISH. [L. s.]
